WALTER C. PARMLEY, OF UPPER MONTCLAIR, NEW JERSEY.

CONCRETE BLOCK CONSTRUCTION.

1,293,898.

Specification of Letters Patent. Patented Feb. 11, 1919.

Application filed March 18, 1918. Serial No. 223,018.

To all whom it may concern:

Be it known that I, WALTER C. PARMLEY, a citizen of the United States, residing at Upper Montclair, in the county of Essex and 5 State of New Jersey, have invented a certain new and useful Improvement in Concrete Block Construction, of which the following is a full, clear, and exact description.

This invention relates to structures composed of blocks, preferably concrete blocks, and the structure may assume a tubular arch 10 or tunnel form, or it may be useful in other forms of construction. The object of the invention is to provide a block construction 15 such that pressure may readily be applied to certain portions of the block without injury to the remaining portions thereof.

The subject matter of this application is substantially a division of certain matter 20 contained in applicant's co-pending application Serial No. 33,681, filed June 12, 1915.

Reference should be had to the accompanying drawings forming a part of this specification, in which Figure 1 shows in 25 perspective a tubular construction embodying applicant's invention; Fig. 2 is an elevation of a portion of a structure embodying one form of applicant's invention; Fig. 3 is an elevation with portions in section showing in detail a modified form of applicant's 30 construction; Fig. 4 is an elevation with portions in detail of a construction embodying the invention; Fig. 5 is a perspective view showing a detail of construction; and Fig. 6 35 is a perspective view showing a detail of construction.

The invention as herein described embodies a tubular concrete construction in which the blocks are laid in successive transverse rows, the blocks in each row abutting 40 against the forward edge of the row against which it is laid. Perhaps the most general use for a structure of the kind herein set forth will be found as a lining for tunnels, 45 although the invention is not limited to this particular use.

In the excavation of tunnels it is very common to use a tunneling machine which works within a shield at the forward or dead 50 end of the tunnel, or by hand excavation to remove the earth under the protection of a shield. As the earth is removed the shield is intermittently moved forward by means of power appliances, such as hydraulic jacks, 55 which push the shield forward, and in this operation the face of the last row of blocks

is made to serve as an abutment against which the ends of the jacks are placed.

The pressure to which the blocks are thus subjected is at times enormous, and under 60 such conditions it is a frequent occurrence for blocks to fracture under the pressure applied. This fracturing of blocks is very frequently, perhaps it might be said generally, due to the condition that blocks in each 65 transverse row or ring do not bear equally and flatly against the blocks in the adjacent ring or row of blocks. In theory there should be complete contact between the adjacent rows of blocks, but in practice this is 70 difficult to attain, and it usually happens for various reasons that the blocks do not match up and engage each other flatly, but that they engage each other irregularly at one or more points, and frequently blocks more or 75 less overhang the edges of an adjacent row of blocks.

In the invention disclosed in this application it is my purpose to provide a form of construction which will remedy or prevent 80 the failure of the blocks under the conditions which have been discussed, and in carrying out this idea I have provided a construction in which the contact portions of each block with an adjacent block in the 85 two rows contiguous to it are at one or two points only, and the points of contact are so arranged with relation to the block that the pressure applied may be transmitted through these points and elements of contact, to the 90 back rows of blocks, and so transmitted through a line, or, more correctly speaking, through an area which is in contact with the succeeding row of blocks, thus relieving the main portion of the block from all or a 95 great portion of the stresses due to the applied pressure.

In Fig. 1 there is indicated a plurality of transverse rows of blocks which are arranged as shown to form in this instance a 100 tubular structure suitable for a tunnel lining.

Preferably the blocks in each row are staggered with respect to its two contiguous rows, although this is not absolutely essential.

The blocks in each row may be constructed in a manner such as shown in Fig. 2, in which the block 2 is provided with portions which in effect form a banded core extending through the block.

The block 2 at the time of molding has inserted therein one or more, in the present

105

110

instance two, spiral members 3. These members are suitably held in proper position within the mold for the block, and the concrete of which the block is made is molded so as to embed these members 3 in the block. It will be obvious that the concrete material fills all the interstices between the convolutions of the members 3 and within the central part of the member 3, so that in the finished block there may be said to be a core of concrete within the member 3 which is banded by the member 3. This produces a core within the member 3 which is of much greater strength per unit of area than the concrete material of the block itself.

These blocks thus prepared may be arranged in a structure such as shown in Fig. 1, so that the core portions of the blocks in succeeding rows of the tunnel structure are in alinement, and when the jacks or other pressure is applied, the pressure will be carried through the successive rows of blocks by the banded or core portions of the blocks in a straight line, or substantially straight line back through the successive rows of blocks.

In Fig. 3 there is a modified construction embodying the same idea as that described with respect to Fig. 2.

In Fig. 3 the block 4 has inserted therein at the time of molding a tubular member 5 which may be a section of pipe or similar section. This pipe at the time of molding is filled with cementitious material either of the same general mix as that composing the block 4, or if desired, a cement of richer mixture may be used with equal facility.

The manner of use of the block shown in Fig. 3 in a finished structure is the same as that described with respect to Fig. 2.

In both of the structures as shown in Figs. 2 and 3, preferably the cementitious material forming what I have termed a core may be made to extend beyond the side surfaces of the block for a short distance, so as to afford a bearing point for a similar core when the blocks are assembled in the structure, such as shown in Fig. 1. These projecting portions may be upon one or both sides of the block as may be desired.

In Fig. 4 the core is made to assume a slightly different form. The block 6 when molded is left with one or more openings, such as indicated at 7, these extending entirely through the block, and are adapted for the reception of a separately made core. As shown in Fig. 4, the core is of cylindrical shape, although it may be of any desired cross sectional shape, and after the core is made and the block is made and hardened, the two may be brought together in the manner suggested in the drawing. Or, the cores may be set in the mold when the block is cast and thus form a part of the block or a part separated therefrom by a layer of paper, etc.

As shown in Fig. 5 the core is made up of a number of sections, indicated at 8, which are assembled upon a rod 9 which serves as a reinforcing member.

The core sections 8 may be made of the same mixture as that of which the block 6 is made, or it may be made of a richer mixture. The core 7 may be held within the opening 14 in any desired manner, and as one way of accomplishing this I may use pitch, paper or any other substance which will cause the core to remain within the opening 14.

In Fig. 6 I have shown a core 10 of continuous structure with a longitudinal member 11 embodied within the same, and extending substantially from end to end. Such a core may, of course, be of any desired cross sectional configuration. Such a core as shown will be inserted in a suitable opening within a block, and held therein by the use of pitch or paper as previously suggested.

With respect to the constructions shown in Figs. 4, 5, and 6, it may be said that the core may be made of the exact length of the block, or it may be made slightly longer than the width of the block, so that the core may extend a slight distance beyond one or both of the faces of the block, as may be desired.

The construction of the block and core as just described has an advantage in that the core under pressure may move with respect to the block, and thus would prevent injury to the block in case of exceedingly high pressure.

If desired, the exposed or extending ends of the cores which have been illustrated in the various figures of the drawings may be made of a cementitious mixture, which is of less strength than that composing the core within the block, so that there may be a slight crushing of the heads of the core for adjustment of this pressure when the pressure exceeds a certain amount.

Having described my invention, I claim:

1. In a structure of the character described, a plurality of contiguous rows of blocks, each of said blocks having one or more core portions extending therethrough which core portions in adjacent rows of blocks are in alinement, each core portion comprising a reinforcing element, and concrete intimately associated with the reinforcing element.

2. In a structure of the character described, a plurality of contiguous rows of blocks each of said blocks having one or more core portions extending therethrough which core portions in adjacent rows of blocks are in alinement, each core portion comprising a metal reinforcing element with which concrete is intimately associated.

3. In a structure of the character described,

2. Probability of getting two or more older elements in a selected group of size n is the probability of getting at least one older element in a group of size n which is the complement of the probability of getting no older elements in a group of size n .

7.1.1. A structure of the extracted features, a probability of the extracted structure being exclusive, and the extracted features are more specific than the extracted features.

10. *Classification of the characters described, partitioned into groups of the same kind*
10. *Classification of the characters described, partitioned into groups of the same kind*

6.3. In the statement of the executed transaction, in the statement whereof, it is hereto attached, it is made by the assignee over a block and seal in signature.
